UNITED STATES PATENT OFFICE

HARRY A. CUMFER, OF CHICAGO, ILLINOIS, ASSIGNOR OF ONE-HALF TO WILLARD J. MASON, OF GREENWICH, CONNECTICUT

MACHINE FOR MAKING MULTIPLY BUILDING BOARD

Application filed June 24, 1929. Serial No. 373,090.

The present invention relates to improvements in a machine for the manufacture of building board, plaster board or the like, and has for one of its principal objects the provision of a device to which a plurality of separate sheets of material are fed, operated upon continuously and united, the resultant product issuing from the machine in a finished condition ready to be packed and marketed.

The device of the present invention has been designed particularly for the manufacture of a building board suitable for use as a plaster base comprising essentially a flat base sheet, one surface of which is coated with an adhesive (which is also preferably a waterproofing material, such as asphalt), while a second sheet is provided with corrugations and is united to the flat base sheet through the medium of the adhesive to produce a unitary structure comprising the flat base sheet and a corrugated sheet adhesively united thereto. This fibrous structure has been used as a plaster base. In one of the preferred types of plaster bases of this character, the corrugated sheet is provided with apertures through which some of the plaster passes to key therewith.

In a co-pending application, Serial No. 250,374, filed January 30, 1928, I propose to unite the cut-outs produced in aperturing the corrugated sheet to the base sheet for two reasons, one, I utilize what was formerly wasted, and two, the upper surface of the cut-out being devoid of adhesive presents a surface having an affinity for plaster. Thus, when the plaster passes through the aperture it will key with the corrugated sheet as well as with the base sheet through the medium of the cut-out united therewith.

Among the important objects of this invention are to provide in a machine for acting on two continuously advancing strips of fibrous material means for corrugating and scoring one sheet; means for then adhesively uniting said corrugated scored sheet with the second uncorrugated sheet; means for completely severing the scored portions and positively attaching the cut-outs thus produced with the uncorrugated sheet, and

means for maintaining the two sheets in positive contact until the adhesive has set sufficiently to permit the composite structure to be cut into board of a size convenient for marketing.

In one preferred embodiment of the invention, the flat base sheet preferably comprises a laminated multi-ply structure made up by uniting a plurality of separate plies, although it is to be understood that the machine is designed to produce a board structure in which either or both the base sheet or the corrugated sheet may comprise one or a number of laminated plies.

In its preferred operation, the machine of the present invention unites the cut-outs to the base sheet immediately opposite to the apertures thus formed in the corrugated sheet.

Another important object of the invention is to provide means for manufacturing a fibrous structure which may be used in place of the usual laths, the plaster being applied to the corrugated surface squeezing into the apertures provided therein, thereby keying the plaster to the board. By means of the present invention the board may be manufactured economically, and due to its waterproofing qualities surpasses the conventional lath.

Other and further important objects of the invention as well as advantages will be apparent from the accompanying drawings and the following description.

In the drawings, Figs. 1 and 1a taken together illustrate in side elevation the machine of the present invention.

Fig. 2 is a top plan view of the device shown in Fig. 1, with parts broken away for clearness.

Fig. 3 is a fragmentary sectional elevational view, partly diagrammatic, illustrating particularly the essential instrumentalities of the machine.

Fig. 4 is a fragmentary sectional view of the product produced by the machine, in contact with the corrugating bar chain.

Fig. 5 is a fragmentary top plan view of a portion of the device shown in Fig. 1a.

Fig. 6 is a transverse sectional view taken

on line 6—6 of Fig. 5 looking in the direction indicated by the arrows.

Referring more particularly to the drawings, 1 indicates generally the frame of the machine, mounted on the front end of which are a plurality of horizontally disposed rollers 2 suitably positioned one above the other. The rollers 2 are adapted to guide a plurality of strips of fiber board 3 to the machine from conventional supply rolls (not shown).

10 A tank or vat 4 positioned adjacent the lower front end portion of the frame 1 is adapted to contain an adhesive material (which is also preferably a waterproofing material), such as asphalt or the like. A pump 5 is positioned within the vat 4 adapted to transfer the adhesive material from the tank to the surfaces of the sheets 3, through an upstanding conduit 6 provided 15 with a series of transversely extended pipes 7 disposed between the strips 3. The strips are then passed through a pair of co-acting pressure rolls 8 and 9, said rolls being mounted in bearing blocks 10 and 11, respectively. The bearing block 11 may be fixed 20 relative to a pair of guides or trunnions 12 comprising a portion of the frame 1, whereas the block 10 may be slidably positioned between said guides. The block 10 may be 25 adjusted vertically by means of a hand wheel 13 mounted at the upper portion of the trunnions. The wheel 13 is rigidly connected to a shaft 14 which has mounted thereon adjacent its ends bevel gears 15 30 (Fig. 2) which in turn mesh with cooperating bevel gears 16 mounted upon adjusting screws 17. In passing through the rolls 8 and 9 the separate strips 3 are adhesively united, forming a laminated board 18.

40 After passing through the pressure rolls 8 and 9, an additional quantity of adhesive material is applied to the upper surface of the board 18. The board 18 then passes through a set of doctor rolls 19 wherein the adhesive material is uniformly spread over 45 the surfaces and then through a set of scrapers 20 where excess adhesive material is removed, the same dropping back into the vat 4.

50 A roller 2', similar to rollers 2, is mounted above rollers 2 upon the frame 1. A strip of fiber board 3' is adapted to be guided by the roller 2' to an auxiliary guide roller 21, from which the strip 3' is directed to a corrugating unit 22, comprising a cylinder 23 (Fig. 3) having longitudinal ribs 24 on its surface. An endless chain of pressure bars 25 is adapted to pass over the cylinder 23, the individual bars 26 being adapted to 55 register with the channels formed between the ribs 24. The cylinder 23 in contact with the bars 26 meshes with a co-acting cylinder 27, provided with a series of alternate large and small ribs 28 and 29. Upon rotation 60 of the cylinders the point of contact of the

two cylinders alternately presents a rib 24 juxtaposed to a rib 28, and a bar 26 to a bead 29, thus producing a corrugated sheet, as shown best at 30 in Figure 4. The cylinder 23 is adjustable with respect to the cylinder 27, the bearing blocks 31 being 70 slideable within the guides 32, the latter being actuated by means of the hand wheel 33, (Fig. 1), shaft 34, and accompanying gears 35 and 36, the adjusting mechanism being 75 similar to that associated with the pressure rolls 8 and 9.

After leaving the corrugating unit 22, the corrugated strip 30 in registration with the bar chain 25 to prevent collapse of the 80 corrugations, passes to a scoring unit 37, which comprises a cylinder 38, having longitudinal ribs 39 formed upon its surface, and a cylinder 40, having a plurality of 85 appropriately spaced scoring dies 41 disposed upon its surface. The scoring dies 41 comprise body members 42 (Fig. 3) provided with central apertures 43 defined by knife edges. Adapted to be positioned in the apertures 43 are resilient plugs 44 which 90 may be constructed of rubber, composition, or may if desired take the form of spring impelled plungers. In operation, the dies 41 are adapted to score, but not completely sever, the crests of the corrugated strip 30; 95 hence, the provision of the resilient plugs 44, which prevent the knife edges from severing the fiber sheet.

In passing from the corrugating unit 22 the lower surface of the corrugated strip 100 30 contacts and slides upon an inclined platform 45, positioned immediately below the path of the bar chain 25. Hence, the corrugated element is held in position 105 by the chain at the top and the platform 45 at the bottom, thereby eliminating the possibility of stretching said strip. After passing through the scoring unit 37, the point of contact of the two cylinders 38 and 40 alternately presents a rib 39 on the 110 cylinder 38 and a series of scoring members 41, then a bar 26 in contact with the two cylindrical surfaces. As shown best in Fig. 3, the rectangular crests 46 are partially cut from the bottom upwardly by the 115 scoring members 41. Although, as shown in the specific embodiment of the device, circular tabs are scored, I do not wish to be limited to any particular configured scoring die.

The cylinder 38 is adjustable relative to the cylinder 40, by means of an adjusting wheel 47 and a cooperating mechanism similar to that associated with the pressure rolls 8 and 9, and the corrugating unit 22.

120 Referring particularly to Fig. 2, a main drive shaft 48 may be positioned parallel to the machine proper, and may be driven by any suitable source of power (not shown), such as an electric motor, power engine, or 125

the like. A bevel gear 49 is suitably keyed to the shaft 48 and is adapted to mesh with a bevel gear 50 rigidly connected to a spur gear (not shown) which in turn is operatively associated with the lower pressure roll 9. This last mentioned spur gear is adapted to mesh with a spur gear 51 operatively connected to the upper pressure roll 8. Hence, the two pressure rolls 8 and 9 turn in synchronism with each other.

Another bevel gear 52, also mounted upon the drive shaft 48 may mesh with a bevel gear 53, which may be rigidly connected to a spur gear 54, which in turn may drive an idler gear 55. The idler 55 may mesh with a spur gear 56 operatively connected to the scoring cylinder 40. The gear 56 may mesh with another gear 57 connected to the upper cylinder 38 of the scoring unit. An idler gear 58 may be interposed between the gear 56 and a gear 59, which latter gear is operatively connected to the lower cylinder 27 of the corrugating unit. The gear 59 may mesh with a gear 60 operatively connected to the upper cylinder 23 of the corrugating unit. Hence, by means of the above described gear train, the corrugating unit and the perforating unit operate synchronously. The spur gears 56, 57, 58, 59 and 60 may all be angularly adjustable to provide a ready means for properly timing the relative positions of the ribs, scoring elements and bars upon the cylinders 23, 27, 38 and 40 in their respective cooperative rotations. This feature is important particularly with regard to corrugating unit 22 inasmuch as the two cylinders 23 and 27 may be so relatively adjusted that a suitable amount of clearance exists between the ribs on the two cylinders and the bars 26. In other words, clearance is provided between the co-acting ribs and bars so that the sides of the corrugations formed in the sheet 3' are not gauged or cut.

The bars 26 are fastened at each end to sprocket chains 61, the bars being spaced appropriately to mesh with the ribs upon the upper corrugating cylinder 23. The bar chain 25 is primarily driven by two sprocket wheels (not shown) rigidly connected to the cylinder 23 and over which the chains 61 travel. The path of travel of the bar chain 25 is substantially rhomboidal, and is guided at each of its corners by a series of sprocket wheels. The sprocket wheels, as above mentioned, guide the chain 61 at the upper acute angle of travel, two sprocket wheels 63 guide the same at the lower obtuse angle of travel, two sprocket wheels 64 guide the same at the lower acute angle of travel, and two sprocket wheels 65 guide the same at the upper obtuse angle of travel. Hence, a continuous path is provided for the bar chain 25, the same being conducted by the sprocket chain 61 over the various wheels described above.

To prevent the bar chain 25 from breaking engagement with the corrugated sheet, when passing from the corrugating unit 22 to the scoring unit 37 and from the scoring unit to the joining unit, the sprocket chain 61 at each side of the bar chain 25 is guided parallel to the platform 45 by means of tracks 45', which may be positioned on each side of the platform 45 and parallel to the surface thereof. By this means the bar chain 25 is positively held in engagement with the corrugated sheet while the same is traveling in an inclined plane.

The corrugated sheet 30 in registration with the bar chain 25, after passing from the scoring unit 37, changes its direction of travel and assumes a substantially horizontal path. Simultaneously upon changing direction, the lower portion of the corrugated sheet 30 is brought into contact with the upper surface of the base sheet 18. Pressure is maintained between the two strips 30 and 18 by means of the sprocket wheels 63, holding the bar chain 25 and sheet 30 in contact with the sheet 18, which in turn is held in contact with the sheet 30 by means of a belt 66 which passes over a cylinder 67, positioned immediately beneath the axis of the sprocket wheels 63. The sprocket wheels 63 and cylinder 67 are both adjustable relative to each other, that is, their centers of rotation may be brought toward or away from each other. The adjusting mechanism comprises hand wheels 68 and 69 for the wheels 63 and cylinder 67, respectively, and associated gear and screw mechanism similar to that described in connection with the pressure rolls 8 and 9, the corrugating unit 22 and scoring unit 37.

It can be readily observed that the corrugated strip 30 is fed to the point of juncture at an angle to the plane of the strip 18. This feature of the device eliminates the possibility of tearing or sliding the corrugations upon the base sheet, since no relative motion of the corrugated strip to the laminated board exists, the travel of the belt 66 and the chain 25 being synchronized. The synchronizing means comprises a sprocket wheel (not shown) rigidly connected to the sprocket wheel 64, which drives a sprocket chain 70, as shown in Fig. 1a, which in turn drives an idler sprocket wheel (not shown), and rigidly connected thereto is a spur gear 71 which meshes with another spur gear 72 rigidly connected to a rear belt pulley 73. Thus, the bar chain 25 and the belt 66 are timed, and no relative motion of translation exists between the two. I do not wish to be limited to the specific means of synchronizing the two above described elements inasmuch as the invention contemplates the use of other suitable timing means.

After leaving the joining members 63 and 67, the composite board 74 travels in regis-

tration with the bar chain 25 and the belt 66 to a punching or knock out roll 75. The belt 66 in its upper travel preferably slides upon the plane surface of a table 76. Sufficient clearance is provided between the table top and the bar chain 25 to produce a slight amount of compression upon the board 74 travelling therebetween. The table is supported throughout its length by a plurality of adjustable supports 77, the adjustment mechanism comprising screws 78 operated by handwheels 79. By this means the proximity of the surface of the table 76 to the bar chain 25 can be regulated.

15 The knockout roll 75 has disposed upon its surface studs or the like 80, which are adapted to contact the scored tabs 81 and completely sever them from the rectangular crests 46. By the same operation the tabs 20 are forcibly applied and adhesively united to the base sheet 18 immediately below the apertures in the crests formed by completely severing the scored tabs. The roll 75 is driven in timed relation with the remaining 25 mechanism by means of a sprocket chain 82, which operatively connects the roll 75 to the remaining rolls in an obvious manner.

After leaving the knockout unit chain 25, belt 66 and board 74 held therebetween 30 travel horizontally along the top of the table. The bar chain 25 may be held in contact with the upper surface of the board 74 by means of guides 83, in which the sprocket chains 61 are adapted to travel. Hence, by 35 adjusting the table upwardly or downwardly a desired amount of pressure may be brought to bear upon the board 74.

If it is desired to apply greater pressure to the bar chain a set of pressure bars 40 84 may be provided. The bars may be adjustable by means of a hand wheel 85 to which is rigidly fixed a bevel gear 86 which meshes with another bevel gear 87 rigidly attached to a screw 88. The screw 88 upon being rotated is adapted to raise or lower a bearing block 89 slidably positioned in guides 90. A rod 91 is journaled in the blocks 89 on each side of the machine and is adapted to be raised and lowered with the 50 blocks 89. Mounted upon the rod 91 adjacent each end thereof is one of the pressure bars 84. The bars 84 upon being lowered rest upon the top of the bar chain 25, as shown best in Fig. 6, and press the bars 26 55 of the bar chain tightly upon the board 74.

Upon travelling a suitable distance along the table 76 to permit the proper setting of the corrugated sheet 30 upon the laminated board 18, the bar chain 25 breaks contact with the board 74, and doubles back over the wheels 64. The board continues to travel along the table 76 and upon leaving the same may, if desired, pass over a rotary brush 92 journaled at 93 in a receptacle 94. The receptacle 94 is adapted to contain a

non-adhesive substance such as talc or the like, and by means of the brush 92, a coating of the same is deposited upon the lower surface of the board 74.

The board then leaves the machine proper 70 and passes to a conveyor (not shown) upon which it is conveyed a predetermined distance to allow the adhesive to cool sufficiently to permit cutting of the board if such operation is desired.

It is to be noted that the machine is designed to corrugate while a continuous strip of fibrous material to be corrugated is being continuously fed at an angle to the horizontal. I have discovered that it is preferable in some cases to corrugate a continuously advancing sheet of fibrous material while it is travelling at an angle to the horizontal rather than to corrugate the same sheet while it is advancing in a horizontal 80 plane.

The reason for this is that it is expedient, when using a base sheet built up of a plurality of plies of individual sheets, to maintain the path of travel of the base sheet in a straight line, inasmuch as the base sheet is generally stiffer and thicker than the corrugated sheet, and, therefore, difficult to bend. Hence, it is advisable to change the direction of travel of the corrugated sheet 90 to conform with that of the base sheet rather than vice versa, and inasmuch as the base sheet is to move in a straight line, it is preferable that this line be in a horizontal plane. Of course it is to be understood that this is 100 not to be taken as a limitation of the invention, since various relative directions of feed may be utilized.

As pointed out in the objects of the invention, the machine essentially comprises means for feeding two separate strips of fibrous material, corrugating and scoring means acting on one sheet, means for uniting the corrugated and scored sheet with the second uncorrugated sheet, means for completely severing the scored portions and uniting the cut-outs thus produced to the base sheet immediately adjacent the apertures thus produced, and means for preventing collapse of the corrugations and maintaining the two sheets in contact until the adhesive has set sufficiently to prevent spreading or creeping.

I claim as my invention:

1. A machine comprising in combination 120 means for uniting a continuously advancing corrugated sheet with a continuously advancing uncorrugated sheet, means acting on the corrugated side of said united structure to completely sever the scored portions 125 of the corrugated sheet and simultaneously positively unite with the cut-outs thus produced to the uncorrugated sheet, and means for maintaining positive contact between the corrugated and uncorrugated sheets after 130

being united to prevent creeping of one sheet relative to the other.

2. A machine comprising in combination, means for feeding a plurality of advancing strips of fibrous material, means for corrugating one advancing strip, means for scoring portions of said corrugated sheet at spaced intervals, means for adhesively uniting said corrugated sheet with a continuously advancing uncorrugated sheet, means for completely severing the scored portions of the corrugated sheet and uniting the cut-outs thus produced to the corrugated sheet, and means for maintaining the corrugated and uncorrugated sheet in positive contact until the adhesive has set sufficiently to prevent creeping between the two sheets.

3. A machine comprising in combination, means for feeding a continuous strip of fibrous material at an angle to the horizontal, means for corrugating said sheet while travelling in said plane, means for scoring said advancing strip at spaced intervals, means for feeding a second strip of fibrous material in a horizontal plane, means for applying adhesive to one of the opposed surfaces of the two continuously advancing strips, means for uniting said continuously advancing strips through the medium of said adhesive, means for carrying said united structure in a horizontal plane, means for completely severing the scored portions of the corrugated strip and positively uniting the cut-outs thus produced with the base sheet, and means for maintaining positive contact between the corrugated and uncorrugated strips until the adhesive has set sufficiently to prevent creeping.

4. A machine for manufacturing plaster board comprising in combination, corrugating rolls for forming alternate ribs and depressions in a continuously advancing sheet, scoring rolls for scoring said ribs at spaced intervals, pressure rolls for adhesively uniting the corrugated sheet to the laminated board, knockout means, comprising a cylinder, the surface of which is provided with a plurality of spaced studs, for severing said scored portions and positively uniting the cut-outs thus formed to the laminated board.

5. A machine for manufacturing plaster board comprising in combination, corrugating rolls for forming alternate ribs and depressions in a continuously advancing sheet, scoring rolls for scoring said ribs at spaced intervals, pressure rolls for uniting a plurality of continuously advancing sheets to form a laminated board, a second set of pressure rolls for adhesively uniting the corrugated sheet to the laminated board, knockout means, comprising a cylinder, the surface of which is provided with a plurality of spaced studs, for severing said scored portions and positively uniting the cut-outs thus formed to the laminated board.

6. A machine for manufacturing plaster board comprising in combination, corrugating rolls for forming alternate ribs and depressions in a continuously advancing sheet, scoring rolls for scoring said ribs at spaced intervals, pressure rolls for uniting a plurality of continuously advancing sheets to form a laminated board, a second set of pressure rolls for adhesively uniting the corrugated sheet to the laminated board, knockout means, comprising a cylinder, the surface of which is provided with a plurality of spaced studs, for severing said scored portions and positively uniting the cut-outs thus formed to the laminated board, and means comprising a continuous chain of transversely extending bars insertable between the ribs of the corrugated sheet in consecutive order to prevent flattening of the corrugations.

7. A machine for manufacturing plaster board comprising in combination, corrugating rolls for forming alternate ribs and depressions in a continuously advancing sheet, scoring rolls for scoring said ribs at spaced intervals, pressure rolls for uniting a plurality of continuously advancing sheets to form a laminated board, a second set of pressure rolls for adhesively uniting the corrugated sheet to the laminated board, knockout means, comprising a cylinder, the surface of which is provided with a plurality of spaced studs, for severing said scored portions and positively uniting the cut-outs thus formed to the laminated board, means comprising a continuous chain of transversely extending bars insertable between the ribs of the corrugated sheet in consecutive order to prevent flattening of the corrugations, and means for maintaining pressure on the corrugated sheet and laminated board after being united to prevent them from separating.

8. A machine comprising in combination, a corrugating unit comprising a pair of co-acting cylinders, the surface of one of which is provided with spaced longitudinal ribs, and the surface of the other of which is provided with a plurality of alternate spaced ribs and spaced beads, an endless chain comprising spaced transverse bars provided with longitudinal grooves adapted to be insertable between the ribs of the first mentioned cylinder, said grooves and the beads of the second cylinder being in register, and means for passing the material to be corrugated continuously between the two cylinders.

In testimony whereof I affix my signature.
HARRY A. CUMFER.
